UNITED STATES PATENT OFFICE.

FRANK CORNELIUS KIRKPATRICK, OF AMORY, MISSISSIPPI.

PLOW-STOCK.

1,144,042.

Specification of Letters Patent. Patented June 22, 1915.

Application filed June 4, 1914. Serial No. 843,037.

To all whom it may concern:

Be it known that I, FRANK CORNELIUS KIRKPATRICK, a citizen of the United States, residing at Amory, in the county of Monroe, 5 and State of Mississippi, have invented a new and useful Plow-Stock, of which the following is a specification.

The invention relates to improvements in plow stocks.

10 The object of the present invention is to improve the construction of plow stocks and to provide a simple, efficient and comparatively inexpensive plow stock of light, strong, and durable construction, capable of 15 ready adjustment to enable the plow stock to work different kinds of shares, shovels, etc.

A further object of the invention is to provide a plow stock having means for adjustably mounting a colter and for enabling 20 the same to be readily removed, replaced, and securely fastened in position for use.

With these and other objects in view the invention consists in the construction and novel combination of parts hereinafter fully 25 described, illustrated in the accompanying drawing, and pointed out in the claims here-to appended, it being understood that various changes in the form, proportion, size and minor details of construction, within 30 the scope of the claims, may be resorted to without departing from the spirit or sacrificing any of the advantages of the invention.

In the drawing, Figure 1 is a central vertical longitudinal sectional view of a plow stock constructed in accordance with this invention. Fig. 2 is a rear elevation of the same. Fig. 3 is a transverse sectional view on the line 3—3 of Fig. 1. Fig. 4 is a transverse sectional view on the line 4—4 of Fig. 1. Fig. 5 is a detail sectional view on the line 5—5 of Fig. 1.

Like numerals of reference designate corresponding parts in all the figures of the drawing.

In the accompanying drawing, in which is illustrated the preferred embodiment of the invention, 1 designates a channeled plow beam designed to be constructed of steel or other suitable material and preferably tapered forwardly and rearwardly from an intermediate point, as clearly shown in Fig. 1 of the drawing. The plow beam 1 is composed of spaced side flanges 2 and a top connecting portion 3, the rear terminals 4 of the side flanges being extended rear-

wardly beyond the top connecting portion to provide lugs or ears which form a bifurcated rear end in which a standard 5 is adjustably pivoted by a transverse bolt 6. 60 The standard, which is also channeled, is composed of spaced side flanges 7 and a connecting portion 8, and is provided in its side flanges with perforations 9^a arranged at intervals at the intermediate portion of the 65 standard and adapted to receive the bolt 6 to permit the rear end of the plow to be connected with the standard at different points along the latter. The standard and the plow beam are also capable of relative pivotal adjustment to arrange the standard to different 70 inclinations, and the parts are rigidly secured in their adjustment by an inclined brace 9, secured at its upper end between the side flanges 2 of the beam by a transverse 75 bolt 10, and having its lower portion extending through a slot 11 in the standard and secured to the latter by a transverse bolt 12. The inclined brace 9 extends upwardly and forwardly from the lower portion of the 80 standard, and its upper end is maintained in a central position between the side flanges 2 of the plow beam by a spacing sleeve 13, arranged on the transverse bolt 10 and provided with a central slot 14 into which the 85 upper end of the brace 9 extends. The slot 11 is formed in the connecting portion 8 of the standard and the lower portion of the inclined brace 9 is provided with a plurality of perforations 15, arranged at intervals 90 and adapted to receive the bolt 12 to permit a relative adjustment of the brace and the standard. The relative adjustment of the standard and the plow beam enables the 95 plow stock to be arranged for working different kinds of plow shares, shovels, and other cultivating blades.

The plow stock is equipped with inclined plow handles 16 located at opposite sides of the standard and arranged at an angle to 100 each other and to the said standard, as clearly illustrated in Figs. 2 and 3 of the drawing. The plow handles, which are connected by upper and lower rungs 17 and 18, are secured at their lower ends to the outer 105 faces of the side flanges 7 of the standard by a transverse bolt 19, and the said plow handles are connected with the upper end of the standard by means of angularly bent arms 20, formed integral with the side 110 flanges 8 and composed of lower or inner laterally extending portions and upwardly

projecting outer portions. The upwardly projecting outer portions of the arms 20 diverge upwardly and fit against the inner faces of the plow handles, being secured to the same by the lower rung 18, which preferably consists of a rod having a head at one end and threaded at the other end to receive a nut 21. By this construction the plow handles are rigidly secured to the standard. 5 The standard is provided at its lower end with a longitudinally curved plate 22, arranged between and extending across the space between the side flanges 7 and having terminal portions 23 and 24 extending upwardly or inwardly and fitted against the inner face of the connecting portion 8 of the standard. The upper terminal portion 24 is riveted to the connecting portion 8 and the said plate or piece 22 is provided between its ends with a bolt opening 25 registering with a bolt opening 26 of the connecting portion 8 of the standard and adapted to receive a fastening device for securing a plow share or shovel to the standard. The 10 rearwardly curved or bowed plate 22 is resilient and operates, in a measure, to cushion the share or shovel.

The plow beam is provided at a point intermediate of its ends, preferably at the apex 30 formed by its tapered portion, with a slot 27, adapted to receive a colter 28, which also extends through a slot 29 of a bracket or plate 30, arranged between the side flanges of the plow and composed of a bottom horizontal portion and upwardly diverging front and rear portions having their terminals riveted or otherwise secured to the inner or lower face of the connecting portion 3 of the plow beam. The colter, which has a tapered 35 lower portion, is provided at the front thereof with a cutting edge 31, and the upper portion of the colter is provided at the front edge with notches 32 forming teeth for engaging the front wall of the slot 27. The slot 27 is formed in the top connecting portion 3 of the plow beam, and the upper notched or toothed portion of the colter is maintained in engagement with the said front wall of the slot 27 by a wedge 33, 40 located in rear of the colter and interposed between the same and the rear walls of the slots 27 and 30. The wedge, which preferably has its upper terminal 34 bent laterally to enable it to be readily grasped, forms a 45 convenient means for adjustably securing the colter to the beam, and it will enable the colter to be readily removed and replaced and it securely fastens the colter to the beam. 50 The beam is provided at its front portion 60 with a plate or member 35 located within the plow beam and extending entirely across the space between the side flanges thereof, and provided at its front end with a vertical flange 36 arranged in flush relation with and 65 closing the front end of the plow beam. The

rear portion 37 of the plate or member 35 is inclined and has a terminal attaching portion 38 fitted against the lower face of the connecting portion 3 of the plow beam and riveted or otherwise secured to the same. The front 70 flange 36 is provided with an opening 39 and the body portion of the plate or member 35 has an opening 40 arranged in vertical alignment with an opening 41 in the connecting portion of the beam. The openings 39, 40 75 and 41 enable a suitable draft attachment to be fastened to the front of the plow beam.

What is claimed is:—

1. A plow stock including a beam, a channeled standard arranged at and extending 80 above and below the rear end of the beam and provided below the same with a slot, said standard being also provided in its side flanges with perforations arranged at intervals, a pivot piercing the rear end of the beam and adapted to be arranged in the perforations of the side flanges of the standard for adjustably connecting the same to the beam, an inclined brace pivotally connected at its upper end to the beam and extending downwardly and rearwardly through the slot of the standard, a fastening device piercing the lower portion of the brace and the side flanges of the standard and adjustable 85 on one of said parts, and handles secured to 90 and carried by the standard in its adjustment.

2. A plow stock including a channeled beam having rearwardly projecting side flanges, a channeled standard adjustably pivoted between the projecting portions of the side flanges, an inclined brace extending downwardly from the beam in advance of the standard and adjustably secured at its lower portion to the standard a fastening 100 device piercing the flanges of the beam and securing the upper end of the brace to the same, and a spacing sleeve arranged on the said fastening device and having a slot receiving the upper end of the brace.

3. A plow stock including a beam, an inclined channeled standard secured to and extending above and below the rear end of the beam and having its side flanges extended at the top of the standard and projecting laterally to form handle supporting arms, and plow handles connected at their lower ends to the standard and supported at an intermediate point by the said arms.

4. A plow stock including a beam, an inclined channeled standard provided at the upper ends of its side flanges with integral laterally projecting arms having terminal diverging attaching portions, said standard being secured to and projecting above and below the beam, and plow handles secured at their lower terminals to the standard and connecting at an intermediate point to the attaching portions of the said arms.

5. A plow stock including a beam, plow

- handles and a channeled standard provided at its lower portion with a curved plate arranged between the side flanges of the standard and having its terminals fitted against the rear 5 face of the connecting portion of the standard, one of the terminals of the said plate being secured to the standard, said plate and standard having aligned bolt openings.
6. In a plow, the combination with a beam, 10 a standard secured at an intermediate point to the end of the beam, said standard having angularly bent arms provided at the top thereof, said arms diverging upwardly and spaced apart, plow handles, means for securing the plow handles to the standard below the beam, and a rung for connecting the said 15 arms to the handles above the beam.

7. In a plow, the combination with a beam, a standard secured to the end of the beam, said standard having angularly bent arms 20 provided at the top thereof, said arms diverging outwardly and spaced apart, plow handles, means for securing the lower ends of the plow handles to a rigid part of the plow, and means for securing the said arms 25 to the inner sides of the handles above the attachment of the standard to the beam.

In testimony, that I claim the foregoing as my own, I have hereto affixed my signature in the presence of two witnesses.

FRANK CORNELIUS KIRKPATRICK.
